[57] **CLAIM**

The ornamental design for a lotto toy, as shown and
described.

DESCRIPTION

FIG. 1 is a perspective view of a transparent bottom portion
of a lotto toy, showing my new design;

FIG. 2 is a top plan view of the transparent bottom portion
of FIG. 1.

FIG. 3 is a front elevation view of the transparent bottom
portion of FIG. 1, the rear elevation view being a mirror
image thereof;

FIG. 4 is a right side elevation view of the transparent bottom
portion of FIG. 1, the left side elevation view being
a mirror image thereof; and,

FIG. 5 is a perspective view of both the top and bottom
portion of the lotto toy.
